[57] CLAIM

The ornamental design for an aerosol can overcap, as shown and described.

DESCRIPTION

FIG. 1 is a top plan view of an aerosol can overcap, showing my new design;

FIG. 2 is a front elevation view thereof;

FIG. 3 is a side elevation view thereof, the opposite side thereof being a mirror image of the side shown;

FIG. 4 is a rear elevation view thereof;

FIG. 5 is a bottom plan view thereof; and

FIG. 6 is a cross-sectional view thereof.

FIG. 1

FIG. 2

FIG. 3

FIG. 4

FIG. 5

FIG. 6
